[57] CLAIM

The ornamental design for the inhalator, substantially as shown and described.

DESCRIPTION

FIG. 1 is a front and right side perspective view of the inhalator according to the invention, the left side thereof being identical to the right side;

FIG. 2 is a front elevational view of the inhalator according to FIG. 1 rotated counterclockwise through 40°;

FIG. 3 is a top plan view of FIG. 2;

FIG. 4 is a bottom plan view of FIG. 2;

FIG. 5 is a rear elevational view of FIG. 2; and FIG. 6 is an enlarged perspective view of the inhalator in closed position.
